CLAIM

The ornamental design for an air conditioner as shown and described.

DESCRIPTION

1. Air conditioner

1.1 : Perspective

1.2 : Front

1.3 : Back

1.4 : Left

1.5 : Right

1.6 : Top

1.7 : Bottom

1.8 : Exploded

1.9 : Perspective view 2

1.10 : Perspective view 3

1.11 : Perspective view 4

The broken lines depict portions of the air conditioner that form no part of the claimed design; this design is for an air conditioner whose bottom cover can be separated as shown in reproduction 1.8; as shown in reproductions 1.9 to 1.11, after separating the bottom cover, the bottom part of this design can be used for various purposes by combining with various modules according to the user's needs; reproduction 1.9 is a perspective view showing the state that the bottom part of the claimed design has been used as a bookshelf; reproduction 1.10 is a perspective view showing the state that the bottom part of the claimed design has been used as a plant stand; reproduction 1.11 is a perspective view showing the state that the bottom part of the claimed design has been used as a showcase.
